CLEANING DEVICE

Robert W. Lamberton, Racine, Wis.

Application June 17, 1957, Serial No. 666,094

1 Claim. (Cl. 15—164)

This invention relates to improvements in portable glass cleaning devices adapted for use in a container for holding water and a detergent.

The principal object of the invention is to provide a glass cleaning device of the stated character which is simple in construction, strong and effective, and easy to assemble and clean. A device of this kind lends itself to a high degree of sanitation and the arrangement and construction of its parts are such that all parts are easily cleaned with a minimum amount of effort.

Another object of the invention is to provide a glass cleaning device including spaced banks of brush holders arranged on supports and which are easily removable for cleaning and replacement in alternate positions.

The invention resides further in certain structural details hereinafter set forth and illustrated in the attached drawings, in which:

Figure 1 is a top plan view of my invention, partially in cross-section.

Figure 2 is a side elevation in cross-section of my invention taken along the line 2—2 of Figure 1.

Figure 3 is a fragmentary view of my device as shown in Figure 2.

With reference to the drawings, the cleaning device, in a preferred form, comprises a holding frame 10 having a hub 11 with a centrally located longitudinally extending aperture 12. Spaced equally about and extending from the outer circumferential surface 13 of said hub 11 are spoke members 14, two of which are anchored at one of their ends in said hub, and another, as designated by the numeral 16, pivotally mounted within a recess cut in said hub and rotatable on a pin 17 extending through said recess and a portion of said hub.

The free end of each of said spoke members is apertured and receives columns 18 extending upwardly a substantial distance at right angles to said spoke and downwardly a short distance from said spoke members. These latter column extensions 18a have a vacuum cup 19 attached thereto in each instance and in operation engage the bottom surface of a tank which may hold water and a detergent.

The upwardly extending portions of the column have spaced recesses 20 cut therein, the purpose of which will be hereinafter explained.

Removably mounted within aperture 12 and extending upwardly therefrom is a shaft 21 which is substantially equidistant from all the columns.

A tuft cleaning brush 22 is secured to the free end of said shaft 21 by means of a locking pin 15, with a second brush 23 slidably mounted on the shaft immediately below said brush 22. The brushes 22 and 23 are comprised of individually bunched fibers 27 secured within cylinders 25 with bunches of said fibers spaced equally about and extending outwardly from the outer circumferential surface of said cylinders.

Slidably mounted on said shaft 21 and between the brush 23 and the hub 11 is an additional brush 23a, similar to brush 23, separated one from the other by

collar 26, also slidably mounted on shaft 21. An elongated collar 26a is disposed between the hub 11 and brush 23a and is also slidable on shaft 21. The tufts 27 extend outwardly from and are spaced substantially equally about the circumferential surface of each tuft holder 27a and are substantially equal in thickness and length.

A number of enlarged removable rings 28 are disposed in the spaced recesses 20 and arranged in spaced relation from adjacent the top of the columns 18 down to and adjacent the top of the elongated collar 26a. Arranged about and spaced equally and extending downwardly at an angle from the inside surface of each ring are long tufts 30, the ends 30a of which in assembled relationship extend below and beyond the free ends of the tufts 27 and below and beyond the tufts of brush 22.

Attention is directed to the fact that each individual bunch of tufts 30 is arranged whereby a portion of one end of each tuft is very closely confined within a ferrule 31 which in turn is closely fitted in an opening 32, a series of which are formed within the rings 28.

An enclosing ring 33 of rubber, or other material having similar characteristics, is arranged about the free ends of the columns 18. This ring 33 is made with three spaced notches 34 which are employed to substantially encase the free ends 35 of the column 18 and initially functions as a lock to hold the rings 28 securely in spaced relationship and in the recesses 20. The inside diameter of the ring 33 is less than the combined radius from the center of shaft 21 to the columns 18 so that to set over the columns 18, the ring 33 must be stretched. The tension thereby created in stretching ring 33 is used to apply tension to the columns 18 when the ring 33 tends to expand to its normal shape and size.

When it is desirable to disassemble the unit, the following steps are followed: The enclosing ring 33 is first removed and spoke 16 is swung downwardly about its pivot point 17. The rings 28 may be readily removed from the recesses 20 and drawn upwardly over the brush 22.

After this is done, the shaft 21, with the brushes and the collars may be withdrawn bodily from the hub 11. As all of the brushes and collars are individually mounted, all or a few may be detached independently from the shaft 21, and it is apparent that such parts can be readily cleaned or easily replaced.

The operation of cleaning glasses in the unit of the present application is easy to carry out. The glass 36 is upended, as shown in Figure 3, to force the open end down over the tufts between the rings 28 and the brush holders. The upwardly extending tufts of the brush 22 are used to clean the inside bottom of the glass while the tufts 27 clean the inside surface of the glass, and the tufts 30, the outside surface of the glass. A mere up and down movement of the glass in the unit provides an effective way to clean the glasses.

Changes in details may be made without departing from the spirit or scope of my invention, but which I claim is new is:

A glass cleaning device comprising a base member having a centrally disposed shaft mounted therein with said shaft extending upwardly at right angles to said base, a plurality of spoke members spaced equally from said base, a plurality of upstanding columns spaced equally from said shaft but remote therefrom adjacent the outer periphery of said spokes and fixed in said spokes, one of said spokes pivoted in said base, extensions to said columns extending below said spokes and having surface contacting elements mounted on the free ends of said extensions, a series of demountable spaced cylinders arranged on said shaft, spaced tufts of fiber arranged equally about and from the outer circumferential surface of each cylinder, said tufts forming a circularly shaped brush, spaced recesses formed in said columns, with like spaced recesses

in each column spaced opposite from each other, a plurality of rings, each ring supported demountably and horizontally in said oppositely disposed recesses, tufts of fibers arranged, about and extending inwardly from the inside circumferential surface of said rings, and forming a circular brush, the free ends of each tuft in said ring, and the free ends of each tuft in said cylinders in opposed relation and in close proximity whereby as the open end of a glass is pressed downwardly between the tufts extending from said rings and said cylinders, the inside and outside surfaces of the glass are cleaned, said rings adapt-

able for disengagement from said recesses upon downward movement of said pivotally mounted spoke.
